UNITED STATES PATENT OFFICE.

CHARLES W. CARMAN, OF SARCOXIE, MISSOURI, ASSIGNOR OF ONE-HALF
TO IRA E. ADAMS, OF SARCOXIE, MISSOURI.

ROTARY ENGINE.

SPECIFICATION forming part of Letters Patent No. 784,248, dated March 7, 1905.

Application filed October 18, 1904. Serial No. 228,967.

To all whom it may concern:

Be it known that I, CHARLES W. CARMAN, a citizen of the United States, residing at Sarcoxie, in the county of Jasper and State of Missouri, have invented a new and useful 5 Rotary Engine, of which the following is a specification.

This invention relates to rotary engines, and has for its principal object to provide a 10 novel form of engine in which provision is made for supplying and exhausting the actuating fluid through the main shaft, the latter being hollow and forming both an inlet and exhaust passage, terminating at ports within 15 the cylinder.

A further object of the invention is to provide a novel form of piston-wing so constructed 20 that dead steam may freely escape from the cylinder in all positions of the wing.

25 A still further object of the invention is to provide an improved means for governing the speed of the engine, and, further, to avoid the danger of leakage of steam by placing a governor and controlling - valve directly in the steam-chest.

30 A still further object of the invention is to provide means whereby the sensitiveness of the governor may be readily adjusted while the engine is running in order to increase or decrease the speed.

With these and other objects in view, as will more fully hereinafter appear, the invention consists in certain novel features of construction and arrangement of parts herein- 35 after fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is 45 a transverse sectional elevation of a rotary engine constructed in accordance with the invention. Fig. 2 is a sectional plan view of the same on the line 2 2 of Fig. 1, the parts being shown in plan. Fig. 3 is a sectional

50 elevation of the end portion of the steam-chest, showing the means for adjusting the tension of the balance-spring. Fig. 4 is a transverse sectional view of the shaft on the line 4 4 of Fig. 2. Fig. 5 is a side elevation of the annular cut-off valve, showing it in 55 position on the hollow shaft of the engine.

Similar numerals of reference are employed to indicate corresponding parts throughout the several figures of the drawings.

The engine is provided with a suitable base 10, that is preferably formed integral with the 60 circular cylinder 11. The heads 12 and 13 of the cylinder may be formed of separate members bolted to the cylinder proper, or one of said heads may be formed integral with the cylinder, as shown in Fig. 2. Through both 65 heads extends a shaft 14, one end of said shaft being supported in a suitable bearing formed in a support 15, that is carried by the base, while the cylinder-head 13 forms a bearing for the opposite end of the shaft. 70 The cylinder-head 12 is provided with a suitable stuffing-box 16 in order to prevent leakage of the steam, and between the stuffing-box and the bearing 15 a combined balance 75 and belt wheel 17 is mounted on the shaft. The size and character of the balance-wheel will of course vary with the horse-power of the engine and the work which it is intended to perform. Within the cylinder is a piston 80 18, that may be formed integral with the shaft or secured thereto, as desired. The piston and the shaft are hollow and the piston is divided into two chambers by a transversely-disposed partition 19. In the wall of one chamber is a steam-inlet port 20, through 85 which steam passes to the cylinder, and in the opposite chamber is a steam-exhaust port 21, from which the steam passes, the steam exhausting at the outer end of the shaft or being conveyed away by a suitable exhaust- 90 pipe. On the ends of the body of the piston are secured disks 22 of a diameter about equal to the internal diameter of the cylinder, and these disks are connected by a piston-wing 23, that is carried by a central portion of the 95 piston. The forward face of the piston-wing

is arranged on a curved line and forms a cam for successively opening movable abutments 24, the abutments being moved outward by the wing and then after the wing has passed 5 being moved inward until their inner edges engage the cylindrical portion of the piston. At the opposite sides of the cylinder are arranged abutment-chambers 25, which may be formed integral with the cylinder-casting, 10 but preferably are formed of separate casings that may be readily detached in order to examine or repair the abutments. The opposite side walls of the abutment-casings form supports for transversely-extending pins 26, 15 on which the inner ends of the abutments 24 are mounted, the blades of the abutments passing through suitable openings formed in the wall of the cylinder and packing-strips 28 being used in order to prevent leakage of steam. 20 These, however, will not in all cases be necessary. In each abutment-casing is arranged a helical compression-spring 29 bearing between the fixed casing and the abutment and serving to restore said abutment to operative position after the passage of the piston-wing. 25

It will be noted on reference to Fig. 1 that the steam-inlet port 20 is arranged in the rear face of the piston-wing, so that it cannot be closed by the inner edge of the abutment. 30 The forward face of the piston-wing is provided with grooves 30, that extend for almost its entire length and merge into the exhaust-port 21, so that with the abutments in the position shown in Fig. 1 the dead steam may 35 freely exhaust from the upper portion of the cylinder and continue to exhaust while the abutment to the left is being forced out by the piston-wing.

The cylinder-head 13 forms one wall of a 40 steam-chest 32, into which the end of the shaft 14 extends, and in the shaft is an opening or openings 33, through which steam may pass from the steam-chest to the hollow shaft and from thence to the cylinder. Mounted on 45 the hollow shaft is a cut-off valve in the form of a flanged ring 34, that is under the control of the governor and may be moved lengthwise of the shaft to increase or decrease the effective area of the openings 33, and thus 50 control the quantity of steam admitted to the engine, in accordance with the speed. The shaft is provided with a transverse slot through which extends the flattened portions of a pair of governor-arms 36, approximately of bell- 55 crank form and connected to the shaft by a pivot-pin 36'. The governor-arms bear against the valve 34 and in operation tend to move the valve in the direction of the cylinder, and thus cut off the flow of steam through the 60 ports 33. This movement, however, is resisted by a comparatively light compression-spring 37, that surrounds the shaft. Against the inner end of the governor-arms bears a ring 39, that preferably is provided with a

cross-bar 39', extending through the transverse slot of the shaft in order that a portion of the ring or a portion of the arm may at all times be in contact with the inner ends of the governor-arms. The ring 39 is held in position by a helical compression-spring 40, 65 that tends to move the governor-arms and the valve-disk to closing position. This spring is in the nature of a balancing-spring and is of less strength than the spring 37. The outer end of the spring 40 bears against a collar or 70 cap 41, that is engaged by a screw 32, disposed in the threaded opening of the outer wall of the steam-chest, and said screw has a milled head, which may be turned in order to increase or decrease the stress of the balancing-spring. In the valve-ring is formed a 75 notch 44, one wall of which is inclined, as shown more clearly in Fig. 5, and said valve is held from revoluble movement by a pin 45, that extends through a suitable opening 80 formed in an arm or disk 38, that is secured to the stationary cylinder, the valve being thus held from revoluble movement.

In the operation of the engine steam or other fluid pressure passes from the chest 90 through the opening or openings 33 to the interior of the hollow shaft and from thence through port 20. The steam-pressure between the rear face of the piston-wing and the opposing abutment 24 causes the piston to 95 revolve in the direction of the arrow, Fig. 1, while dead steam escapes from that portion of the cylinder in advance of the wing and passes through the port 21, thence out through the opposite end of the hollow shaft. As the piston-wing rotates the abutments are successively moved into their respective casings, 100 and after the passage of the piston-wing said abutments are restored to working position by the springs 29. During the operation of 105 the engine the governor will control the position of the cut-off valve, and as each port passes beyond the inclined shoulder of the notch 44 it will be placed in communication 110 with the steam-chest, and steam will pass therethrough and flow to the hollow shaft and cylinder. As the shaft continues to revolve the port will pass under the inclined wall of the notch, and the flow of steam will be gradually cut off, and the point of cut-off will depend on the position of the valve with relation 115 to the shaft. If the engine is running at high speed, the valve will be moved nearer the cylinder, and the cut-off will occur more quickly than if the engine was running slowly. If the 120 speed decreases, the spring 37 will force the disk 34 in the direction of the governor-arms, and the weighted ends of the latter will be moved inwardly. This increases the effective 125 area of the ports and the quantity of steam admitted to the engine. By turning the adjusting-screw the stress of the balancing-spring may be altered, and this alteration in the sen-

sitiveness of the governor will permit any desired increase or decrease of the speed of the engine.

Having thus described the invention, what is claimed is—

1. The combination in a rotary engine, of a cylinder, a revoluble piston disposed therein and provided with steam inlet and exhaust passages, a piston-wing having in its opposite faces ports in communication with said passages, the forward face of said wing being curved to form a cam and being grooved from the hub to its extreme outer end to permit the escape of steam to the exhaust-port, and pivotally-mounted abutments movable outward by engagement with the cam-face of said wing.

2. The combination in a rotary engine, of a cylinder, a piston, a hollow shaft forming a steam-passage, a steam-chest into which the shaft extends, said shaft having an opening through which steam may pass from the chest, a valve controlling the area of said opening, and means for adjusting the position of the valve in accordance with the speed of the engine.

3. The combination in a rotary engine, of a cylinder, a piston disposed therein, a hollow shaft carrying the piston, a steam-chest into which the shaft extends, there being an opening in said shaft for the passage of steam from the chest, a valve movable longitudinally of the shaft, a spring tending to prevent movement of the disk to closing position, and a centrifugal governor carried by the shaft and controlling the position of said disk.

4. The combination in a rotary engine, of a cylinder, a piston disposed therein, a hollow shaft carrying said piston, a steam-chest into which the shaft extends, there being an opening formed in the shaft for the passage of steam from the chest, a valve mounted on the shaft, a spring tending to prevent movement

of the disk to closing position, a centrifugal governor carried by the shaft and controlling the position of the disk, and means for positively limiting movement of said disk.

5. The combination in a rotary engine, of a cylinder, a piston disposed therein, a hollow shaft carrying said piston, a steam-chest into which the shaft extends, an opening being formed in the shaft for the passage of steam from the chest, a valve carried by the shaft, a spring tending to resist closing movement of said valve, a governor controlling the position of the valve, a balancing-spring for said governor, and a screw extending through a threaded opening in the wall of the steam-chest and serving as a means for adjusting the stress of the balancing-spring.

6. The combination with a revoluble piston, of a hollow ported shaft, a steam-chest into which the shaft extends, and a governor-controlled valve in the form of a revoluble flanged ring surrounding said shaft and notched or recessed, the ports of the hollow shaft coming successively into alignment with said notch or recess as the shaft revolves.

7. The combination with a piston, of a hollow ported shaft, a steam-chest into which said shaft extends, a non-revoluble valve-ring mounted on the shaft, and provided with a notch or recess, one wall of which is inclined, governor-arms extending through a transverse slot in the shaft and bearing against the valve-ring, and a spring-pressed ring bearing on said governor-arms and tending to move the weighted ends of the same inward toward the shaft.

In testimony that I claim the foregoing as my own I have hereto affixed my signature in the presence of two witnesses.

CHARLES W. CARMAN.
